UNITED STATES PATENT OFFICE.

JAY G. HUNTER, OF SABULA, IOWA.

COMPRESSOR.

Application filed July 6, 1920. Serial No. 394,243.

To all whom it may concern:

Be it known that I, JAY G. HUNTER, a citizen of the United States, residing at Sabula, in the county of Jackson and State of Iowa, 5 have invented certain new and useful Improvements in Compressors, of which the following is a description.

My invention belongs to that general class of devices known as compressors and relates 10 particularly to a compressor especially adapted for use in connection with refrigerating systems. The invention has among its objects the production of a device of the kind described that is simple, convenient, efficient, 15 durable, compact, accessible and satisfactory for use wherever found applicable. The invention has among its further objects the production of a compressor that will not easily get out of order or repair, but which 20 may be adjusted or inspected without disassembling the entire machine, the same being so accessible that almost any part may be readily examined. Many other objects 25 and advantages of the construction herein set forth will be obvious to those skilled in the art from the disclosure herein made.

To this end my invention consists in the novel construction, arrangement and combination of parts herein shown and described 30 and more particularly pointed out in the claims.

In the drawings, wherein like reference characters indicate like or corresponding parts,

35 Fig. 1 is a sectional view through the compressor taken substantially on line 1—1 of Fig. 2;

Fig. 2 is a sectional view taken on line 2—2 of Fig. 1;

40 Fig. 3 is an enlarged sectional view similar to a portion of Fig. 1;

Fig. 4 is a sectional view taken substantially on line 4—4 of Fig. 3; and

45 Fig. 5 is a sectional view taken on line 5—5 of Fig. 3.

Referring to the drawings, I have illustrated a twin-cylinder, single-acting, vertical, enclosed type of compressor, it being understood that the same may be of suitable 50 size and material and that one or more cylinders may be employed. As shown, 1 represents the crank case provided with a suitable base 2, cylinders 3, 3 and the cylinder heads 4—4. A description of one cylinder 55 and associated parts will be sufficient for both, as they are similar. The crank case 1

is provided with an extending part or flange 5 for each cylinder, the same being preferably flanged as at 6 to form a support for the cylinder. The cylinder 3 is outwardly 60 flanged as at 7 to correspond with flange 6 on the crank case, the two parts being preferably secured together by means of bolts 8 or their equivalents for the purpose. One of the flanges, as shown, flange 6, is provided with a groove 9, while the other, as shown, flange 7, is provided with a tongue 10 arranged to seat in the groove and form a tight joint. The tongue and groove also serve to accurately center the cylinder on the 70 crank case and afford a more rigid construction. The cylinder head 4 is secured in place on the upper end of the cylinder 3 by bolts 11 or their equivalents, a groove 12 and tongue 13 being provided on the parts 75 so that a tight joint is secured at this point. It may be mentioned that the upper part of the cylinder is preferably formed with cooling fins 15, the bolts 11 extending through and engaging the fins, or where preferred, the 80 fins may be connected at the bolts to provide a boss for each bolt and affording more rigid construction. As shown, the cylinder is also provided with a jacket or outer wall 16 for a portion of its length spaced from the inner 85 wall of the cylinder to provide a water jacket space 17.

The cylinder is provided with an intake port or inlet 19 which connects with an intake pipe 20. The same is also provided 90 with an outlet or discharge port 21 which is enlarged as at 22 and preferably extends around the cylinder the cylinder being provided at some suitable point for attachment of the discharge pipe 23 which communicates with space 22. It will be noted that with this style of discharge port the discharge of the gas may take place from all sides so that the discharge may be rapid and there is no slamming of 100 the valve, but a quick discharge at all times. I have shown an opening opposite the discharge pipe 23, which may be closed by a plug 24. In connecting up the device pipe 20 extends from and connects with the 105 refrigerating system, as for example, the accumulator, while pipe 23 extends to and is connected with the condenser or the equivalent.

The crank case 1 is provided with cover or 110 end plates 26 and 27. As shown, plate 26 is formed with a bearing 28 for the end of

shaft 29, it being understood that bushings may be employed, if desired, the plate and bearing being strengthened or stiffened by the ribs 30. The plate 26 is secured in place 5 on the crank casing by means of bolts 31 or their equivalents, and I prefer to arrange the cooperating groove and tongue construction 32--33 between the crank case and the end plate so as to afford a gas and oil tight fit. 10 The same also centers the plate and shaft bearing. If desired, an opening may be arranged at the end of the bearings, but I normally close this by a plug 34, or its equivalent. The bearing may also be provided 15 with an oil hole 35. The plate 27 at the opposite end of the crank case is formed with a bearing part 37 which may be braced or strengthened by the ribs 38 and 39 at the inner and outer sides of the plate. In this 20 case the shaft extends through the plate and bearing, however, and I arrange a stuffing box so that packing 40 may be arranged around the shaft and afford a tight fit. The packing is maintained in place by the adjustable member or gland 41 which may be extended as at 42 to engage with the outer end of the bearing 37, as shown. The plate in this case is secured to the crank case similar to the plate 26 by means of the bolts 31, 25 the tongue and groove construction being also employed. In this case I also provide an oil opening 35' so that this bearing is properly lubricated. In addition to the assembled end plates 26 and 27, I provide a 30 cover plate or plates 43 on one or both sides of the crank case, these being secured in place by bolts or the equivalents. As most clearly shown in Fig. 2, a pulley or driving wheel 44, which may also serve as a flywheel, 35 is arranged on the shaft 29 at the end which projects to the exterior of the crank case through the bearing on plate 27. The pulley and flywheel 44 may be driven from any source of power, such as a gas, oil, heat or 40 steam engine, electric motor or their equivalents.

Arranged on the shaft 29 is a member 46, there being one for each cylinder, as shown, the same being similar. Member 46 is secured on the shaft by means of the set screw 47 and key 48, and the same is provided with an eccentric or extending portion 49 (see Figs. 1 and 2). The part 49 takes the place of a crank pin on the shaft and affords a 55 considerable bearing area. This construction permits a straight shaft to be used, and affords a long stroke without sacrificing strength, or increasing the sizes of the parts unreasonably. The piston or crank rod 50 is provided with an eccentric strap 51 arranged to embrace the eccentric portion 49, the same being preferably split at one side as shown and normally secured together at the split portion by a bolt 52 or the equivalent. The opposite end of the rod 50 is pro-

vided with a wrist or piston pin bearing portion 53 arranged to cooperate with the part 54 and embrace the piston or wrist pin 56, bolts 55 locking the parts together. Shims and bearing metal may, of course, be employed in accordance with recognized engineering practice, and are unnecessary to be described. 70

Arranged in each cylinder is a piston, preferably of the double trunk type having 75 each end provided with piston or snap rings of the desired type arranged to prevent an excess of oil getting into the cylinders and to shut off the live gas to the shaft or crank case. By this arrangement the bearings, 80 etc., in the crank case are not permitted to frost over, nor is the oil ever in danger of freezing. As most clearly shown in Figs. 1 and 3, I provide the rings 58 adjacent the lower end of the piston and the rings 59 adjacent the top, there being any desired number of rings. The piston is provided with one or more, preferably a plurality of openings 61, through the wall thereof, the piston being cut away or of reduced external diameter, 85 however, between the rings so as to provide a space 62 communicating with the openings 61 and the chamber 53 at the interior of the piston. A plate 64 or its equivalent preferably carried by the flanges 65 on the piston, 90 however, substantially closes or separates the chamber 63 from the crank case. The upper end of the piston is provided with an opening 67, the passage of gas through the opening, however, being normally controlled by 95 a suction valve 69. The valve 69 is provided with a portion 68, the valve being of greater diameter. The part 69 is adapted to cooperate with the valve seat 71 on the piston. It will be noted that the piston is preferably countersunk as at 72 and the valve portion 69 may be grooved at 73 to provide a cushion effect. The movement of the valve 68 is limited by pins 75 carried by the part 100 68 and arranged to engage the piston. As shown, two pins are employed, between which is arranged a spring 76. The piston, as most clearly shown in Figs. 4 and 5, is provided with opening at each side of part 105 68, a portion of the piston end being cut away or notched at 77 to form the openings. On the inner side, the piston is provided with the recesses 78 on opposite sides between the openings 77. When the member 110 68 is seated and the pins in operation, as shown in Fig. 3, they normally engage the inner part of the piston in the recesses 78. In seating the part, the part 68 is pushed down into place with the pins 75 in the openings 77 and after the same is seated, the part 68 is given a quarter of a turn in either direction so that the pins are brought into the recesses 78. The cam shaped faces on the extending parts 79 retract the springs 76 in positioning the part so that it may be 115 120 125 130

turned, and these same faces tend to prevent the accidental turning of the part so that the pins may release the under side of the piston. Part 68 is controlled by a spring 80 5 or its equivalent bearing against the under side of the part and the plate 64. If desired, plate 64 may be provided with an extending part or boss 81 arranged to center and maintain the spring centrally relative 10 to part 68.

Arranged in the upper part of the cylinder is a discharge valve 82 of the desired size and shape. As shown, the valve 82 is formed with a valve face 84 arranged to 15 operate with the seat 83 at the discharge port 21. If desired, an opening 91 may be provided in the head 4, and the same connected with a pressure gauge.

Plate 64 is preferably provided with a 20 pending part or oil drip 86 and bearing part 54 with an oil opening 87, the purpose of the same being more fully explained hereafter. I have shown a sprocket wheel 89 carried by the parts 46, the sprocket wheel 25 carrying a lubricating carrier in the form of a chain 90. If desired, the crank case may be stiffened by a rib 88 on the interior, as shown, or if preferred, on the exterior. I have shown the bottom of the crank case 30 provided with a groove, the same constituting a grit and dirt trap or well. As shown, piping extends to and from and connecting the water jackets in the two cylinders. One of the pipes, for example 23, may be the feed 35 pipe, 94, the connecting pipe and 95 the discharge pipe connecting so that water or the like may be circulated through the spaces 17, keeping the cylinders cool at that point.

The operation of the device may be briefly 40 described as follows, assuming that pipe 20 is connected with the accumulator or its equivalent, pipe 23 with the condenser in the refrigerating system, and assuming also that shaft 29 is driven from any suitable 45 source of power and the crank case is provided with the desired amount of oil or lubricant. As the shaft is driven, the two pistons are reciprocated. Referring to Fig. 1, it will be noted that the piston is at the 50 bottom of its travel and the valve 69 is open. The gas in the chamber 63, space 62, and from the pipe 20 may enter and pass through the opening 77 to above the piston, this taking place while the piston is traveling downward to the position shown. As 55 the piston travels upward, the gas above the valve 69 is compressed in the cylinder, and lifting the valve 82, passes through the circumferential discharge port 21 and out 60 through pipe 23 to the condenser, forcing the same thereinto under pressure. As soon as the piston starts to return to the position shown in Fig. 1, valve 82 immediately seats, preventing the gas from entering the cylinder 65 from the condenser, and valve 69 car-

ried by part 68, owing to the suction as well as the spring 80, immediately opens and fresh gas, for example, ammonia gas, is drawn in above the piston. The operations described continue as the machine continues 70 to operate. The oil in the crank case is splashed by the mechanism, and if the level of the oil is low, is carried up on the parts 46 by the chain 90 and thoroughly lubricates all the moving parts. The taper of parts 75 46 cause the oil to flow toward the eccentrics. A portion of that thrown up into the cylinders not only lubricates the cylinder walls, but splashes into the piston and accumulating on the plate 64, flows down the projecting drip part 86 and drops into the oil opening 87, lubricating the wrist pin and bearing. Some of the oil also drops from the parts and passes through the opening 35 and 80 35' to lubricate the shaft bearings. 85

It will be noted that with my construction the crank case may be readily inspected by removing the cover plates 43 or the end plates 26 or 27. By removing the cylinder cover 4, valve 82 is fully exposed and may be readily removed, and if this valve is removed, the valve 69 and the upper end of the piston is fully exposed. If part 68 and valve 69 are removed, the same being given a quarter of a turn and lifted out as described in assembling the same, the interior chamber 63 of the piston is fully exposed, and if plate 64 is then removed, the upper ends of the crank or piston rods 50 and their bearing are exposed. By removing the 90 bolts 55 and parts 54, the pistons may be removed, through the top of the cylinders without taking the cylinders from the crank case or even opening the crank case. It will, therefore, be seen that the device is 105 readily and conveniently accessible for adjustments or for inspection and repairs without removing the cylinders from the crank case or the pistons from the cylinders, and that any necessary adjustment, renewal 110 or repair may be made without disturbing the pipe connections. This in itself is of considerable importance. Owing to the water and air cooling, as well as perfect lubrication, there is never any danger of the compressor overheating. The compressor, owing 115 to its simplicity, accessibility, compactness, efficiency, as well as economy in construction due to its superior design, is especially suitable for small refrigerating plants or the 120 like, but, however, it may be constructed for large as well as small installations. While I have particularly mentioned the same as a compressor for refrigerator systems, and for compressing ammonia gas, the essential as 125 well as the non-essential details make the same suitable for other uses.

Having thus described my invention, it is obvious that various immaterial modifications may be made in the same without de- 130

parting from the spirit of my invention; hence I do not wish to be understood as limiting myself to the exact form, construction, arrangement and combination of parts 5 herein shown and described or uses mentioned.

What I claim as new and desire to secure by Letters Patent is:

1. In a device of the kind described and 10 in combination, a crank case having detachable end plates each provided with a shaft bearing, a cylinder having intake and discharge ports and detachably mounted on said crank case, a detachable cylinder head 15 for said cylinder, a piston arranged in said cylinder, a shaft rotatably carried by said bearings, a piston rod operatively connected with said piston and said shaft, said piston provided with a chamber therein open at 20 each end and in communication with said intake port, a valve in the end adjacent the cylinder head, means for detachably securing said valve in place, a detachable spring held plate arranged transversely across the 25 piston at a point between the ends of the piston, and a valve arranged to prevent the admission of fluid into the cylinder through the discharge port.

2. In a compressor of the kind described 30 and in combination, a tubular piston provided with a port in the side wall thereof, a plate arranged transversely of the piston at one side of said port, a valve member arranged at the other side of said port and 35 opening outwardly, means for detachably retaining said valve on the piston, yieldable means intermediate said valve and plate for moving said valve to its open position and releasably holding said plate closed.

40 3. In a compressor of the kind described and in combination, a tubular piston provided with a port in the side wall thereof, a detachable plate arranged transversely of the piston at one side of said port, a valve 45 member arranged at the other side of said port, means for detachably retaining said valve on the piston, and yieldable means for controlling said valve and said plate.

4. In a compressor of the kind described 50 and in combination, a tubular piston provided with ports in the side wall thereof, a removable plate arranged transversely of the piston at one side of said ports, a valve member arranged at the other side of said 55 ports and opening outwardly, means for retaining said valve on the piston and limiting the movement thereof, and yieldable means for moving said valve to its open position and also holding said plate in position.

60 5. In a device of the kind described and in combination, a tubular piston provided with ports in the side walls thereof, a plate extending transversely of the piston, at one 65 side of said ports, a valve extending trans-

versely of the piston at the other side of said ports, means for limiting the opening movement of said valve, means for normally maintaining the valve in its open position, a rod arranged at the crank end of the piston and means for securing the rod to the piston, said means releasable from the opposite end of the piston upon removal of the valve and plate therefrom and without removing said piston from its cylinder.

75 6. In a device of the kind described and in combination, a cylinder having intake and discharge ports, a piston reciprocatory in said cylinder and having a chamber therein in communication with said intake port and provided with a port through its head, a valve for closing said last-mentioned port and extending into said chamber, means for normally yieldably maintaining said valve unseated to keep the port open, and means for preventing relative rotation between said valve and piston.

80 7. In a device of the kind described and in combination, a cylinder having intake and discharge ports, a piston reciprocatory in 90 said cylinder and having a chamber therein in communication with said intake port and provided with a port through its head, a valve for closing said last-mentioned port and extending into said chamber, means for 95 yieldably maintaining said valve unseated to keep the port open, and means for preventing relative rotation between said valve and piston, comprising a radial extension on one of said parts adapted to removably enter 100 a recess provided in the other of said parts.

8. In a device of the kind described and in combination, a cylinder having intake and discharge ports, a piston reciprocatory in 105 said cylinder and having a chamber therein in communication with said intake port and also provided with an opening leading from said chamber through the head end thereof, and formed with a valve seat at the head end of said opening, said opening counterbored 110 to provide an open channel at one side from the chamber to the seat, and also counterbored to provide a radial recess therein at the chamber, a valve slidable through said opening and adapted to seat on said valve 115 seat, said valve having a radial recess therein at its lower end, a pin in said recess adapted to enter said radial recess of the piston to prevent relative rotation between the piston and valve, and a spring yieldingly pressing 120 said pin radially outwardly.

9. In a device of the kind described and in combination, a cylinder having intake and discharge ports, a piston slidable therein and having a chamber in communication 125 with said intake port and also provided with an axial opening from said chamber to the head end, said axial opening channelled from end to end along a pair of circumferentially spaced lines, and also provided with a pair 130

- of radial recesses at the chamber spaced intermediate said channels, a valve slidable in said opening and seating at the upper end thereof to close said channels and provided
5 with a radial bore therethrough at the lower end projecting into the chamber, a pair of pins slidable in said bore and a spring between the opposed ends of said pins, whereby said pins will be yieldably pushed outwardly
10 to engage in the radial recesses of the piston and prevent relative rotational movement between it and said valve.
10. In a device of the kind described and in combination, a cylinder, a tubular
15 piston having a chamber therein, a piston rod pivotally connected to said piston and
- having an aperture communicating with its bearing, and a plate arranged in said piston transversely of the lower end of said chamber above said rod and provided with a depending projection thereon, whereby the lubricant splashed onto said plate will be directed by said projection into said aperture at the piston rod bearing.
- In testimony whereof, I have hereunto signed my name in the presence of two subscribing witnesses.

JAY G. HUNTER.
